UNITED STATES PATENT OFFICE.

SEBASTIAN ZIANI DE FERRANTI, OF LONDON, ENGLAND.

SPINNING-MACHINE.

1,013,872.

Specification of Letters Patent.

Patented Jan. 9, 1912.

Application filed August 3, 1905. Serial No. 272,560.

To all whom it may concern:

Be it known that I, SEBASTIAN ZIANI DE FERRANTI, a subject of the King of Great Britain and Ireland, and residing at 31 5 Lyndhurst road, Hampstead, London, N.W., England, have invented certain new and useful Improvements in and Relating to Spinning-Machines, of which the following is a specification.

10 The invention relates to spinning, doubling, twisting and like textile processes hereinafter referred to generically as "twisting".

The invention, though not restricted to 15 such an application, is specially advantageous when used in connection with the spinning machine described in my Patent No. 927343.

One object of the invention is to provide 20 a ready means for imparting a right or left hand twist to the material at will.

Another object of the invention is the provision of means for the simultaneous control of a number of turbines each driving 25 its own spindle.

Another object is the provision of simple means for retarding a lagging part.

Further objects of the invention will appear in the following specification.

30 To these ends the invention consists in the improved combinations of elements hereinafter described and particularly set forth in the claims.

Referring to the accompanying drawings: 35 Figure 1 shows a vertical section through a ring flier provided with a reversible turbine; Fig. 2 shows a horizontal section of the same; Figs. 3 and 4 show means for simultaneously controlling a number of such 40 turbines; Fig. 5 shows magnetic means for retarding a lagging part; Fig. 6 shows a detail of the means employed for simultaneously varying the operative action of a plurality of sets of feed rolls, one of the 45 friction wheels being removed to show forked lever, while Fig. 7 shows a general view of one form of the entire machine, and Fig. 7^a a cross-section on the line A B of Fig. 7 to an enlarged scale showing telescopic drive.

The drawings are to a large extent of a diagrammatic nature, while corresponding parts in the different figures are denoted by the same reference symbols.

50 In carrying the invention into effect according to one form as applied to a twisting

machine having leading and lagging parts; the leading part, (see Figs. 1 and 2,) consists of a ring flier, *a*, having mounted thereon rings, *b* and *c*, of oppositely disposed turbine blades. Nozzles, *d* and *e*, are arranged as shown to coöperate with these sets of blades, one for each direction of rotation. The ring flier runs with air lubrication in an accurately turned sleeve, *f*, which by way of rubber rings, *h*, is supported in the housing or casing, *i*, of the ring flier, this casing, *i*, being in turn supported in the rail, *j*. The exhaust of the turbine serves to take a proportion of the dead weight of the ring flier by acting on the underside of its flange, *k*, past which it finally escapes. In order to slow down or stop the ring flier without removing this air support, baffles, *m*, arranged on a pivoted arm, *n*, may be employed, which by operation of the arm on which they are mounted can be disposed to a greater or less extent between the nozzles and the turbine, thereby to a certain extent cutting off the supply of motive fluid thereto. The arms, *n*, may be operated in any convenient manner, such for example, as by the rod, *o*, having a collar, *p*, which engages with the tail-piece, *r*, when moved longitudinally, a 55 spring, *s*, serving to replace the baffle.

In order to control a number of turbines fitted one each to their corresponding spindles, I may divide the main air supply, *t*, (see Fig. 3), into two branches, *u* and *v*, a three-way valve, *w*, being placed at the junction point of the branches. The one branch, *u*, is provided with a series of nozzles, *x*, for one direction of rotation, while the other branch, *v*, is provided with a second series of nozzles, *z*, for the other direction of rotation. By operation of the valve, *w*, it will be seen that working fluid may be led simultaneously to all the turbines in either direction of rotation at will. This device involves only one valve for a set of turbines. A development, however, of such an arrangement is shown in Fig. 4, where the branch pipes, *u* and *v*, as before, lead air to the nozzles, *x* and *z*. Each of these nozzles is controlled by a valve, those for one direction of rotation being indicated at 2, and those for the other direction at 3. The master valve, *w*, as before controls all the valves, 2 and 3, all the valves being linked together as indicated in the figure by rods, 4, and bell cranks, 5, so that by operation of

the handle, 6, the one set of valves, 2, can be rendered inoperative and the other set, 3, simultaneously rendered operative.

The ring flier is provided at its lower 5 part with a thread-engaging device such as the hook, 7, and in the machine described forms the leading part. A cylindrical extension, 8, may be conveniently fitted into the top of the ring flier, (see Fig. 7,) in 10 order to minimize the effects of ballooning.

The lagging part in the machine described consists of a spindle or bobbin-carrier, 9, a series of such spindles being mounted on trough-shaped rails, 10, containing gearing, 15 11, which connects the spindles to the shaft of square cross-section, 12, transmitting motion to the feed rolls, 13. The shaft, 12, carries at its upper end a friction wheel, 14, splined thereon, which engages with a friction disk, 15, fixed to the lower roll, 13. Any suitable gear is provided for traversing the friction wheel, 14, across the disk, 15, that indicated by way of example consisting of a forked lever, 16, carried on the 20 shaft, 17, and operated by a worm quadrant, 18, worm, 19, and hand wheel, 20. Reversal is obtained by moving the friction wheel, 14, across the surface of the friction disk. As seen in Fig. 6, the shaft, 30 17, may be common to a number of spinning units, and have mounted thereon a corresponding number of levers, 16, so that reversal is effected simultaneously in the different units, by operation of the hand 35 wheel, 20. The trough-shaped rails, 10, as described may be conveniently mounted one at the front and the other at the back of the machine, being supported at the end of a see-saw lever, 22, operated by way of the 40 links, 23 and 24, from the heart-shaped cam, 25, and co-acting roller, 26, the cam being driven by any convenient means independent of the twisting motors.

In order to impose a certain amount of 45 drag on the lagging part, a device, 27, (see Fig. 5,) similar to the squirrel-cage rotor of an induction motor, may be mounted on the lower end of the spindle. This rotor is disposed between the jaws of an electro- 50 magnet, 28, provided with energizing coils, 29. A screw, 30, (see also Fig. 7,) having a worm wheel, 31, passing through the bend of the magnet and being operated by the worm, 32; lugs, 33, passing over pins, 34, 55 may be fitted on the magnet, so as to guide it when moved up and down by the screw, 30. The effect of moving the magnet up or down is to vary the reluctance of the magnetic circuit, and thus the drag on the 60 spindle. As will be seen in Fig. 5, a number of such magnets may be operated from a common shaft, 35, having mounted upon it a hand wheel, 36, this shaft carrying the worms, 32, which gear with the operating 65 screws of the magnets. As seen in Fig. 5,

the lower member of the telescopic shaft, 12, may conveniently be disposed within the bend of the magnet, 28.

The main air supply, (see Fig. 7,) is shown at 37, branch pipes, 38, controlled by valves, 70 39, operated for example by the pull rods, 40, distributing the motive fluid to the different turbines.

The parts so described are mounted on any suitable frame, 44, forming a support 75 for the different twisting units.

The general operation of the complete machine is as follows: The thread from the bobbins, 41, retarded to a proper extent by the box-shaped floats, 42, immersed in water 80 in the troughs, 43, passes by way of the feed rolls, 13, through the anti-ballooner, 8, to the hook, 7, of the ring flier. The bobbin on which the material is to be wound, mounted on the spindle, 9, is drawn around 85 by the thread and reciprocated by the mechanism shown, its motion being transmitted by the telescopic shaft and friction gear to the feed rolls. The twisted material is in this way evenly laid upon the bobbin. Supposing now it is desired to change the direction of twist from right hand to left hand, the right hand set of turbine nozzles will be rendered inoperative and the left hand set 90 rendered operative by means of any of the controls described. This alteration alone, however, would have the effect of altering the direction of rotation of the feed rolls, and in order to maintain their direction constant the hand wheel, 20, is actuated so as 100 to move the levers 16, and thereby move the friction wheels 14, across the disk 15, from one side of the center to the other. In this way the direction of twist is altered while the direction of feed is maintained constant. 105

Although I have described the best way known to me of carrying my invention into effect, nevertheless such example is to be taken as merely illustrative and is not intended to restrict the scope of the invention. 110

Having now described my invention what I claim as new and desire to secure by Letters Patent is:—

1. In a machine for twisting fibrous material, the combination of a rotatable twisting element; means acting to transfer said material in a certain direction; a driving connection between said twisting element and said transferring means; means for driving said twisting element in either direction at will, together with means for maintaining constant said certain direction of transfer. 115

2. In a machine for twisting fibrous material, the combination of a rotary twisting element; rolls feeding the material forward; means for driving said rolls from said twisting element together with means for reversing the direction of rotation of said twisting element, and means for maintaining constant 120 the direction of rotation of said feed rolls. 125

3. In a machine for twisting fibrous material, the combination of a plurality of twisting units each comprising a lagging part, electro-magnetic means for retarding each of said parts, said means including a magnetic circuit, together with means for simultaneously adjusting the reluctance of said circuits. 70
4. In a machine for twisting fibrous material, the combination of a lagging part; electro-magnetic means for retarding said part, said means including a magnetic circuit, together with means for adjusting the reluctance of said circuit. 75
5. In a machine for twisting fibrous material, the combination of a plurality of rotatable twisting elements; means co-acting therewith to transfer said material in a certain direction, a driving connection between 80
- 20 said twisting elements and said transfer means; means for reversing the direction of rotation of said twisting elements and a single instrumentality common to a plurality of said twisting elements for maintaining 85
- 25 constant said certain direction of transfer. 90
6. In a machine for twisting fibrous material, a plurality of twisting units; a separate reversing turbine driving each of said units; means for controlling the flow of 95
- 30 working fluid to each of said turbines; mechanical interconnections between said controlling means, together with a single instrumentality for operating said controlling means by way of said mechanical interconnections. 100
7. In a machine for twisting fibrous material, a plurality of twisting units; separate turbine means driving each of said units, said turbine means having blades for each 105
- 40 direction of rotation; sets of means for controlling the flow of working fluid to each of said turbines, one set for each direction of rotation; mechanical interconnections between the individual members 110
- 45 of each such set, together with means for simultaneously rendering one set of said controlling means operative and the other set inoperative. 115
8. In a machine for twisting fibrous material, a rotary element; a turbine driving the same, said turbine having blades and nozzle means directing fluid thereupon; together with a movable shield disposable between said blades and said nozzle means. 120
- 55 9. In a machine for twisting fibrous material, the combination of a plurality of rotatable twisting elements; means co-acting therewith to transfer said material in a certain direction; a driving connection between 125
- 60 said twisting elements and said transferring means; means for driving said twisting elements in either direction at will, and means for simultaneously maintaining constant said certain direction of transfer. 130
- 65 10. In a machine for twisting fibrous material, a plurality of twisting units, a separate reversing turbine driving each of said units; means for controlling the flow of working fluid to each of said turbines; mechanical interconnections between said controlling means, together with a single instrumentality for operating said controlling means by way of said mechanical interconnections. 70
11. In a machine for twisting fibrous material, the combination of a rotatable twisting element; means acting to transfer said material in a certain direction; a driving connection including a reversible gear between said twisting element and said transferring means, together with means for driving said twisting element in either direction at will. 80
12. In a machine for twisting fibrous material, means for imparting right or left hand twist to said material at will, said means including a plurality of rotatable twisting elements, and separate reversible prime movers for driving the same; together with means for supporting said twist-imparting means. 90
13. In a machine for twisting fibrous material, means for imparting right or left hand twist to said material at will, said means including a rotatable twisting element, transfer means therefor, driving connections between said twisting element and said transfer means, and a separate reversible motor driving said twisting element; together with means for supporting said twist-imparting means. 95
14. In a machine for twisting fibrous material, means for imparting right or left hand twist to said material at will, said means including a rotatable twisting element and a reversible turbine driving the same; together with means for supporting said twist-imparting means. 105
15. In a machine for twisting fibrous material, means for imparting right or left hand twist to said material at will, said means including a rotatable twisting element and a rotor member of a reversible prime mover mounted thereon; together with means for supporting said twist-imparting means. 110
16. In a machine for twisting fibrous material, a plurality of twisting units each including a rotatable twisting element and a separate prime mover driving the same, together with a single instrumentality for reversing the direction of rotation of each of said prime movers. 120
17. In a machine for twisting fibrous material, a plurality of twisting units each including a rotatable twisting element and a separate prime mover driving the same, together with means for simultaneously reversing the direction of rotation of said prime movers. 125

18. In a machine for twisting fibrous material, a plurality of twisting units each including a rotatable twisting element and a turbine driving the same, together with a single instrumentality for reversing the direction of rotation of each of said turbines.
19. In a machine for twisting fibrous material, a plurality of twisting units, each including a rotatable twisting element and a turbine driving the same, together with means for simultaneously reversing the direction of rotation of said turbines.
20. In a machine for twisting fibrous material, means for imparting right or left hand twist to said material at will, said means including a twisting unit having a

rotatable member, a second member guiding material thereto, and a reversible prime mover actuating said unit; means for producing a relative reciprocatory motion between said rotatable member and said second member together with means independent of said unit-actuating prime mover for driving said motion-producing means. 20

In testimony whereof I have signed my 25 name to this specification in the presence of two subscribing witnesses.

SEBASTIAN ZIANI DE FERRANTI.
